(57) **CLAIM**

The ornamental design for a cutting board assembly, as
shown and described.

DESCRIPTION

FIG. 1 is a perspective top front right exploded view,
showing my new design;

FIG. 2 is a perspective top rear left view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a top right perspective view of the cutting board
assembly in a fully assembled state.

The broken lines showing the portions of the cutting board
assembly form no part of the claimed design.

1 Claim, 9 Drawing Sheets
